UNITED STATES PATENT OFFICE.

WILLIAM JOHNSON HOLLAND, OF ERA, TEXAS.

WHEEL.

SPECIFICATION forming part of Letters Patent No. 412,848, dated October 15, 1889.

Application filed July 6, 1889. Serial No. 316,683. (No model.)

To all whom it may concern:

Be it known that I, WILLIAM JOHNSON HOLLAND, a citizen of the United States, residing at Era, in the county of Cooke and State 5 of Texas, have invented a new and useful Wheel, of which the following is a specification.

The invention relates to improvements in wheels. Heretofore great difficulty has been 10 experienced in the construction of wheels in putting the axle-box in the hub and getting it true.

The object of the present invention is to obviate the above difficulty and improve and 15 strengthen the construction of wheels, and especially the manner of securing the spokes in the hubs.

The invention consists in the construction and the novel combination of parts, herein 20 after fully described, and illustrated in the accompanying drawings.

In the drawings, Figure 1 is a perspective view of the hub and spokes. Fig. 2 is a longitudinal sectional view of the hub, the spokes 25 being shown in elevation. Fig. 3 is a transverse sectional view. Fig. 4 is a perspective view of the axle-box. Fig. 5 is a similar view of a modification of the axle-box. Figs. 6 and 30 7 are detail views of the lower end of one of the spokes.

Referring to the drawings, A designates a hub, which is composed of two sections A', that are adapted to be clamped around an axle-box B by means of suitable bands C, where- 35 by the necessity of driving and welding the axle-box in the hub is dispensed with and the adjustment of said box B is rendered easy. In order to prevent the displacement 40 of the axle-box B, the latter is provided at each end with laterally-projecting flanges b, which are wedge shape in cross-section, whereby they may easily be forced into a wooden hub, but suitable recesses a are provided in the metal hub A to receive the flanges b. 45 The axle-box B is provided at its ends with annular flanges b', which engage shoulders a' of the hub and prevent longitudinal movement of the box.

The sections A' of the hub A are construct-

ed of suitable metal and are fitted closely together, and are designed to be coated on their meeting faces with some suitable substance to exclude moisture from the axle-box; and the said sections are provided with suitable sockets a², which are adapted for the reception of spokes D, which, after being inserted in the sockets a², are wedged from the inner face of the sections of the hub A, which will successfully prevent the spokes leaving the sockets. The wedges E are preferably three 60 in number, two e running one way and one e' the other, the wedge e' preferably being in three pieces for convenience.

The spokes D, which are provided with suitable shoulders, are strengthened by metallic 65 braces F, which are arranged at the sides of the spokes and have their lower ends enlarged, which prevents the braces leaving the sockets of the hub A. The braces have their upper ends secured to the spokes by bands G, 70 which are provided with bolts which pass through the spokes and braces and prevent the bands slipping.

In Fig. 5 I have illustrated an axle-box having lateral flanges b at its sides, but no 75 annular ones at its ends, which adapts the axle-box for wagons designed for light work; and I desire it to be understood that I do not limit myself to the precise details of construction herein shown and described, as I may, 80 without departing from the spirit of the invention, make various minor changes therein.

From the foregoing description and the accompanying drawings the construction, operation, and advantages of the invention will 85 readily be understood.

What I claim is—

1. A wheel provided with an axle-box having the lateral flanges b at its sides and the annular flanges b' at its ends, substantially 90 as described.
2. The combination, in a wheel, of the hub, the spokes, the metal braces arranged on each side of the spokes and having enlarged or wedge-shaped lower ends, and bands securing 95 the upper ends of the braces, substantially as described.
3. A wheel comprising the sectional hub,

the bands securing the sections together, the axle-box having the annular flanges b' and the lateral flanges b , wedge-shaped in cross-section, and the spokes wedged from the inside of the hub, and the metal braces having their lower ends enlarged, substantially as described.

In testimony that I claim the foregoing as my own I have hereto affixed my signature in presence of two witnesses.

WILLIAM JOHNSON HOLLAND.

Witnesses:
